JOHN MARTINO AND JOHN CURRIE, OF PHILADELPHIA, ASSIGNORS TO ORR, PAINTER & CO., OF READING, PENNSYLVANIA.

Design No. 4,818, dated April 18, 1871.

DESIGN FOR A PARLOR-STOVE.

The Schedule referred to in these Letters Patent and making part of the same.

We, JOHN MARTINO and JOHN CURRIE, of the city of Philadelphia and State of Pennsylvania, have invented and produced a new and original Design for Parlor-Stoves, of which the following is a specification.

The nature of the design is fully represented in the accompanying photographic illustrations, to which reference is made.

The bottom plate A of the stove has a projecting hearth, *a*. The rest of the plate is of circular form, corresponding to the body of the stove.

The edge is formed of a quarter round, *b*, vertical narrow member *d*, and cove *e*.

The cove has a running ornament, *f*.

In the middle of the panels B B, in the front of the ash-pit, are registers C C having at each vertical side a leafed ornament, *g*.

The cap-ring D of the ash-pit is of similar form, in its cross-section, to that of the bottom plate A, with the exception of an additional upper rounded member *b'*, on which there is a border, *h*.

The projecting edge of the rim has a scalloped ornamentation.

The fire-pot E is of swelled form, and has a projecting flange, F, which has a running ornament, *j*, around its outer edge.

The lower portion of the fire-pot, below the flange, has spreading scroll and leaf ornaments G, the said ornaments being divided by laps *k* having a succession of leaves.

Around the fire-pot, above the flange F, are twin elliptical openings H H above the ornaments G, in which mica is placed.

Around the openings are egg-moldings I, beneath which are leaf ornaments *m*.

A crown ornament, *n*, makes a finish with the upper ends of the twin moldings I, there being leaf or-

naments *o o* which branch out from the crown *n* and overhang the upper ends of the moldings.

The cap-plate I of the fire-pot is of like form, in its cross-section, to that of the edge of the bottom plate A. The edge of the rim has a scalloped ornamentation.

The cylindrical part K has four panels, L.

The front one is provided with a register, C', like the registers C C of the ash-pit.

The panels L have elliptical beads *m'*, which have side ornaments *p p* and end ornaments *p' p'*.

The latter finish with corner ornaments *q q q q*.

The outer projection of the ornaments *p p p' p'* and *q q q q* approximate to the rectangular form of the panels L.

The panels are separated by the vertical moldings *r*, which extend from the annular bottom molding *s* to the molding *s'*.

The crown-plate M of the cylindrical part K is of ogee form in its cross-sections, and has a succession of ornaments, *t*, around it.

The ogee section of the cover N has a succession of leaf ornaments, *u*.

The overhanging edge *v* of the cover is scalloped, and has a running vine of zigzag form.

The upper portion of the cap is carved to make a finish with its lower portion.

The urn O has vertical flutes.

The cover of the urn has open-work *w*.

We claim as our invention—

The design for parlor-stove, as shown and described.

In testimony whereof we have hereunto set our hands and seals this day of March, 1871.
